WINDOW FRAME AND SASH

Michael Mosolgo, Perth Amboy, N. J.

Application June 23, 1948, Serial No. 34,711

3 Claims. (Cl. 20—52.2)

1

This invention relates to new and useful improvements in window frame and sash structures.

According to the invention, a window frame is provided having separate vertical slideways for each of more than two, preferably three, independently raisable and lowerable sashes, such slideways at the sides of the window frame; and opposite these sashes, and preferably outward therefrom, is, a larger sash for filling the entire window frame opening, said larger sash being readily removable from the window frame by withdrawal into the room past the sliding sashes.

Said outer sash, having one or more glass paned sections, is thus removable to allow of easy and safe washing of the outer surfaces of such panes, or for repair or replacement of the sash.

Because of more than two independently raisable and lowerable sashes as above, these can be variously placed at a succession of different levels relative to each other to permit easy and safe access to the panes thereof for successive washing of the outer surfaces of their panes, from the inside of the room.

Another feature is a pivotally mounted auxiliary sash carried by the outer sash, and thus carried opposite a lowermost open section or subdivision of the outer sash; said auxiliary sash adapted to act as a swingably adjustable air inlet means and so modifiable as a ventilating agent. The direction of flow of the ventilating air current is controlled also by the relative heights at which the sliding sashes may be positioned.

A further feature of the invention is the elimination of the necessity for sash cords and weights or for spring torsion substitutes, this feature involving the use of very light weight sashes, the light weight of each sash in considerable part resulting from the fact that more than two sliding sashes are present; in combination with a simple and practicable resiliently mounted structure carrying the three slideways at one side of the window opening for all the sliding sashes, and an associated means for adjusting the resilient action of such mounting, to vary its thrust relative to the slideways for the sliding sashes, thereby nicely to predetermine the frictional engagement between said sashes and their slideways. The resilient means now referred to may also be adjusted if and when desired to permit removal of any or all of the sliding sashes.

For further comprehension of the invention, and of the objects and advantages thereof, reference will be had to the following description and

2

accompanying drawing, and to the appended claims in which the various novel features of the invention are more particularly set forth.

In the accompanying drawing forming a material part of this disclosure:

Fig. 1 is an elevational view looking at the interior side of a window frame and sash structure constructed in accordance with the present invention.

10 Fig. 2 is an enlarged horizontal section, taken on the line 2—2 of Fig. 1.

Fig. 3 is a similarly enlarged vertical section, taken on the line 3—3 of Fig. 1.

15 Fig. 4 is a view similar to Fig. 3, but showing a rear arrangement of the parts for a selected kind and degree of ventilation.

Fig. 5 is a slightly enlarged partial vertical section, taken on the line 5—5 of Fig. 3.

20 Fig. 6 is a view similar to Fig. 4, illustrating a structural modification.

The window frame and sash construction, according to the first form of the invention shown in Figs. 1 to 5, includes a window frame 10 having side members 11, a cap or top sill 12, and a

25 bottom sill 14.

Three sliding glass paned sashes 15, 16 and 17 are provided to completely close the window frame opening; each such sash preferably of the same height. The heights of these sashes are 30 such that when the sash 15 is at the top of the window frame opening, and the sash 17 is at the bottom of said opening, the sash 16 may be arranged with its top properly overlapping the bottom of the sash 15 and its bottom properly overlapping the top of the sash 17.

At each side of the window frame three slideways for said sashes are provided by three grooves in a bar or plate shaped to carry four parallel ribs to establish said grooves. One of such plates, 40 marked 18, extends as shown in Fig. 3 from the top to the bottom of the window frame opening; and is suitably fixed in the recess 19 (Fig. 2) in the window frame.

At the other side of the window frame, the plate 20, presenting the three slideways for the adjacent sides of the sashes 15, 16 and 17, is housed movably in the recess 21; this plate 20 being adapted to be resiliently urged against the sashes 15, 16 and 17 by way of a long leaf spring 45 22 behind the plate 20.

The spring 22 is bowed as indicated in Fig. 2, and its tension is adjustable by spiral adjustment of a pair of screws 24 the heads of which lie beyond the outer sides of a pair of upper and 50 lower arcuate clips 25 at the exterior of the ad-

ja⁵cent side member 11 of the window frame. The shank of each screw 24 goes through a suitable aperture in its associated clip 25, and thence through and in threaded engagement with an internally threaded bushing 26; as shown best in Fig. 2.

The inner ends of said screws bear against the ends of the spring 22, see Figs. 1 and 2, and so by tightening or loosening the screws 24 the frictional grip of the slideways of the plates 18 and 20 relative to the sashes 15, 16 and 17 may be increased or diminished to the desired extent. Also, by fully loosening the screws 24, any or all of the said sashes 15, 16 and 17 may be removed whenever desired.

The sash for filling the window frame opening at an outward location comprises a frame 27, which, with its bottom seated on a stepped-down ledge 28 on the bottom sill 14, and while resting against a pair of stops 29 at the opposite sides of the window frame, is held in place by a pair of locking devices each including a slide bolt 30 guided through eyes 31 on the frame 27 and having an L-extension 32 constituting a finger piece; whereby the bolts may be entered into suitable keeper recesses in the window frame, as indicated at 33 in Fig. 1.

The illustrated outer sash is one for summer time use, and the frame 27 thereof is shown as having two closures of differing types separated by the cross frame member 34. Such upper closure is a glass pane 36, and such lower closure is a screening 37, the latter bottomed by a cross frame member 35. The opening below said member 35 is closable by an auxiliary sash comprising a frame 38 carrying a glass pane 39, this frame hinged at its front bottom as at 40 to the front bottom of the frame 27 of the outer sash.

Said auxiliary sash, swingable into the plane of the frame 27, is thus retained by a latch of any suitable type, here shown as in the form of a latch plate 41 pivoted at 42 (Fig. 5) and carrying an offset operating finger piece 43.

The auxiliary frame 38 is thus swingable to the position shown in Fig. 3 to that shown in Fig. 4, or to any selected less angle of inclination from the vertical, to modify as desired a ventilating inlet for air additional to that admitted through the screening 37; the ventilating air being further controlled by the relative arrangement of the sliding sashes 15, 16 and 17, for instance, as shown in Fig. 4, or as shown in Fig. 3. Extreme flexibility of ventilating control is thereby possible; as, for further example, to admit the ventilating air at the bottom of the window frame opening, and/or to admit said air at the top of such opening, and/or to admit said air at an intermediate point along the height of such opening.

As a further example, the manner of ventilating may be that indicated by the relative positions of the sliding sashes 15', 16' and 17' of the modification of Fig. 6 (these sashes corresponding respectively to the sashes 15, 16 and 17); it here being explained that the sole purpose of including Fig. 6 is to illustrate a further addition which may be made to the summer time outer sash, to wit, the suitable fixation to the latter, at its bottom subdivision openable by the auxiliary ventilating frame 37' (corresponding to the frame 37), of a supplementary frame 44 closed by the screening 45.

In all other respects than that just noted, the structure of Fig. 6 is exactly like that of Figs. 1-5.

For use in the winter time, there may be sup-

plied an outer sash exactly like that of Figs. 1-5, except that in lieu of the screening 37, a glass pane will be in the subdivision of said sash between the cross frame members 34 and 35. Or, 5 for winter time use, to provide complete storm window protection, yet avoid the need for a special winter time outer sash, the outer sash of Figs. 1-5 may have its screening 37 so set therein that the same may be readily removed and a glass pane inserted in substitution therefor.

In order to remove the outer sash, as to facilitate the substitution just referred to, or for the purpose of substituting a special winter time outer sash, or to permit easy and safe washing of the 15 outer surfaces of the glass pane or panes of the outer sash, all that is required is to withdraw the bolts 30 from their keepers, and then, by pull on the handle 32, to swing the top of the outer sash toward the right in Fig. 3, and then the three sliding sashes 15, 16 and 17 all having been fully lowered, to bodily transfer the outer sash to the room interior.

Washing of the outer surfaces of the glass panes of the sashes 15, 16 and 17 is also easy and safe. 25 The most convenient procedure is thus to wash the pane of a particular sash 15, 16 or 17 while that sash is all the way down in the window frame and the other two of said sashes are all the way up in the window frame; so that, in the case of 30 each of the successive washings of the outer surfaces of the panes of the three sashes 15, 16 and 17, the window frame will be open above the sash being washed. Due to the three sliding sashes, such window frame opening not only will always 35 be available during washing, but be of ample size for comfortably reaching in behind the sliding sash at the bottom of the window frame for complete cleaning of the outer surface of its glass pane.

40 While I have illustrated and described the preferred embodiments of my invention, it is to be understood that I do not limit myself to the precise constructions herein disclosed and the right 45 is reserved to all changes and modifications coming within the scope of the invention as defined in the appended claims.

Having thus described my invention, what I 50 claim as new, and desire to secure by United States Letters Patent is:

1. Resilient mounting for a vertically extended elongated plate slidably mounted in a complementary recess formed in the vertical portion of a window frame and which plate has vertical slideways in its outer face engaged by the adjacent vertical sides of window sashes, comprising an elongated bowed leaf spring, the recess being of a depth considerably greater than the thickness of the plate, said spring being within 55 the recess and engaging the inner face of the plate intermediate of its ends and having its ends directed away from the inner face of the plate, and means on the vertical portion of the window frame and engaging the ends of said leaf spring 60 for controlling the tension of said leaf spring against the inner face of the plate.

2. Resilient mounting for a vertically extended elongated plate slidably mounted in a complementary recess formed in the vertical portion of 70 a window frame and which plate has vertical slideways in its outer face engaged by the adjacent vertical sides of window sashes, comprising an elongated bowed leaf spring, the recess being of a depth considerably greater than the thickness of the plate, said spring being within the 75

recess and engaging the inner face of the plate intermediate of its ends and having its ends directed away from the inner face of the plate, and means on the vertical portion of the window frame and engaging the ends of said leaf spring for controlling the tension of said leaf spring against the inner face of the plate, said spring tensioning means comprising screws threaded through the vertical portion of the window frame and having their inner ends abutting the ends of said spring.

3. Resilient mounting for a vertically extended elongated plate slidably mounted in a complementary recess formed in the vertical portion of a window frame and which plate has vertical slide-ways in its outer face engaged by the adjacent vertical sides of window sashes, comprising an elongated bowed leaf spring, the recess being of a depth considerably greater than the thickness of the plate, said spring being within recess and engaging the inner face of the plate intermediate of its ends and having its ends directed away from the inner face of the plate, and means on the vertical portion of the window frame and engaging the ends of said leaf spring for controlling the tension of said leaf spring against the inner face of the plate, said spring tensioning means comprising screws threaded through the vertical portion of the window frame and having their

inner ends abutting the ends of said spring, said screws having heads at their outer ends spaced from the adjacent face of the vertical portion of the window frame, arcuate spring clips having apertures intermediate of their ends through which the shanks of the screws freely rotatively extend, said clips having their free ends abutted against the said adjacent face of the vertical portion causing said clips to bear frictionally against the heads of the screws holding them in desired adjusted rotative positions.
